CLAIM

The ornamental design for an engine cover, as shown and described.

DESCRIPTION

FIG. 1 is a top perspective of the engine cover showing our new design;

FIG. 2 is a bottom perspective of the engine cover from FIG. 1;

FIG. 3 is a top plan view of the engine cover from FIG. 1; FIG. 4 is a bottom plan view of the engine cover from FIG. 1;

FIG. 5 is a right-side elevation of the engine cover of FIG. 1;

FIG. 6 is a left-side elevation of the engine cover of FIG. 1; FIG. 7 is a back elevation of the engine cover of FIG. 1; and, FIG. 8 is a front elevation of the engine cover of FIG. 1. In the drawings, the broken lines depict unclaimed subject matter only and form no part of the claimed design.
